UNITED STATES PATENT OFFICE

THEODORE A. MILLER, OF AKRON, OHIO, ASSIGNOR TO THE AKRON STANDARD MOLD COMPANY, OF AKRON, OHIO, A CORPORATION OF OHIO

COLLAPSIBLE TIRE-BUILDING DRUM

Application filed June 30, 1928. Serial No. 289,484.

The general purpose of the invention is to provide an improved collapsible drum or form especially for building tires in semi-flat form, the beads, when using this type of drum, being applied to the tire carcass on reduced shoulders at the sides of the drum.

The particular object of the invention is to provide a sturdy, quick-acting, collapsible drum construction capable of securing a high degree of contraction to permit easy removal of the finished tire carcass, the actuation of the various sections of the drum being positive to effectively withdraw them from the adherent carcass and preferably being actuatable by a single operating member.

A further object of the invention is to provide a collapsing mechanism for such drums adapted to separate the adjoining sections slightly from the key section to permit free action thereof when it is removed from the core.

A further object of the invention is to provide an improved form collapsing mechanism adapted to be self-locking in expanded condition.

The foregoing and other objects of the invention are attained in the collapsible drum construction shown in the accompanying drawings and described below. It is to be understood that the invention is not limited to the particular form thereof shown and described.

Of the accompanying drawings,

Figure 1 is an elevation of a collapsible drum embodying the invention, the drum being shown expanded;

Figure 2 is a similar view thereof, the drum being shown collapsed;

Figure 3 is a section on line 3-3 of Figure 1; and

Figure 4 is a section on line 4-4 of Figure 1.

Referring to the drawings, the numeral 10 designates the usual drive shaft on which

is secured the chuck 11 having rigidly secured thereto one drum section 12.

Section 12 has hinged onto its opposite ends drum sections 13 and 14, and an intermediate section 15, opposite section 12, is arranged to 50 complete the drum, this section constituting a key section, and having the usual draft as indicated at 16, 16.

Key section 15 is supported on a bar 17 slide- 55 able on chuck 11 in a groove defined by gibs 18, 18 secured on the face of the chuck and additionally guided in its movement by shaft 10 which extends through a slot 19 in said bar.

Sections 13 and 14 are connected to said bar 17 for actuation thereby as the key section is 60 actuated, links 20 and 21 being respectively pivoted to said sections at 22 and 23 and pivotally connected to the bar 17 respectively at 24 and 25. The pivots 22 and 23 are sub- 65 stantially at diametrically opposite points and pivots 24 and 25 are relatively above said diameter, i. e. relatively nearer to the key section so that as the key section is moved in- 70 wardly, links 20 and 21 act as a toggle to expand sections 13 and 14 slightly to provide easier withdrawal of the key section.

To actuate the above-described collapsing drum, a toggle mechanism is provided com- 75 prising a lever 26 pivoted on the chuck at 27, and a lever 28 pivoted at 29 to bar 17, levers 26 and 28 being hinged at 30. An operating handle 31 is secured to lever 26.

The toggle levers 26, 28 are of such length as to maintain the drum section 15 in the core section when actuated slightly past a "dead 80 center" as shown in Figure 1. One of said levers has a stop 32 thereon and the other a pin 33 to prevent collapsing of the toggle levers in their positions past dead center whereby the drum is automatically locked in 85 expanded condition.

In collapsing the drum, the handle 31 is swung downwardly and through the toggle levers draws bar 17 downwardly, the latter withdrawing the key section, slightly spread- 90

ing the sections 13 and 14 as the key section passes out of the drum circle and finally drawing the sections 13 and 14 inwardly after the key section, bringing the parts to the position 5 shown in Figure 2.

Modifications of the invention may be resorted to without departing from the spirit thereof or the scope of the appended claims.

What is claimed is:—

10. 1. A collapsible tire building drum comprising a chuck, one drum section secured thereto, second and third drum sections hinged to the opposite ends of the first drum section, a key section intermediate the second and third sections, a bar supporting the key section and slidable on the chuck, links connecting the hinged section to the bar whereby movement of the key section inwardly of the drum will first slightly expand 20 and then collapse the hinged sections after the key section, and means for collapsing and expanding the drum comprising a toggle connected to the chuck and bar and constructed to lock slightly past a dead center position 25 to hold the drum expanded.
15. 2. A collapsible tire building drum comprising a chuck, one drum section secured thereto, second and third drum sections hinged to the opposite ends of the first drum section, a key section intermediate the second and third sections, a bar supporting the key section and slidable on the chuck, links connecting the hinged section to the bar whereby movement of the key section inwardly of the drum will first slightly expand 30 and then collapse the hinged sections after the key section, and means for collapsing and expanding the drum comprising a toggle connected to the chuck and bar and constructed to lock slightly past a dead center position 35 to hold the drum expanded.
20. 3. A collapsible tire building drum comprising a chuck, one drum section secured thereto, second and third drum sections hinged to the opposite ends of the first drum section, a key section intermediate the second and third sections, a bar supporting the key section and slidable on the chuck, links connecting the hinged section to the bar whereby movement of the key section inwardly of the drum will first slightly expand 40 and then collapse the hinged sections after the key section, and means for collapsing and expanding the drum comprising a toggle connected to the chuck and bar.
25. 4. A collapsible tire building drum comprising a chuck, one drum section secured thereto, second and third drum sections hinged to the opposite ends of the first drum section, a key section intermediate the second and third sections, a bar supporting the key section and slidable on the chuck, links connecting the hinged section to the bar whereby movement of the key section inwardly of the drum will first slightly expand 50 and then collapse the hinged sections after the key section, and means for collapsing and expanding the drum comprising a toggle connected to the chuck and bar and constructed to lock slightly past a dead center position 55 to hold the drum expanded.
30. 5. A collapsible tire building drum comprising a chuck, one drum section secured thereto, second and third drum sections hinged to the opposite ends of the first drum section, a key section intermediate the second and third sections, a bar supporting the key section and slidable on the chuck, links connecting the hinged section to the bar whereby movement of the key section inwardly of the drum will first slightly expand 60 and then collapse the hinged sections after the key section, and means for collapsing and expanding the drum comprising a toggle connected to the chuck and bar and constructed to lock slightly past a dead center position 65 to hold the drum expanded.

collapsing and expanding the drum comprising a toggle connected to the chuck and bar.

5. A collapsible tire building drum comprising a chuck, one drum section secured thereto, second and third drum sections hinged to the opposite ends of the first drum section, a key section intermediate the second and third sections, a bar supporting the key section and slidable on the chuck, links connecting the hinged section to the bar whereby movement of the key section inwardly of the drum will first slightly expand and then collapse the hinged sections after the key section, and means for collapsing and expanding the drum, said means being operatively associated with said bar and adapted to lock automatically to hold the drum expanded. 70

6. A collapsible tire building drum comprising a chuck, one drum section secured thereto, second and third drum sections hinged to the opposite ends of the first drum section, a key section intermediate the second and third sections, a bar supporting the key section and slidable on the chuck, links connecting the hinged section to the bar whereby movement of the key section inwardly of the drum will collapse the hinged sections after the key section, and means for collapsing and expanding the drum, said means being operatively associated with said bar and adapted to lock automatically to hold the drum expanded. 75

7. A collapsible tire building drum comprising a chuck, one drum section secured thereto, second and third drum sections hinged to the opposite ends of the first drum section, a key section intermediate the second and third sections, a bar supporting the key section and slidable on the chuck, links connecting the hinged section to the bar whereby movement of the key section inwardly of the drum will first slightly expand and then collapse the hinged sections after the key section, and means for collapsing and expanding the drum, said means being operatively associated with said bar. 80

8. A collapsible tire building drum comprising a chuck, one drum section secured thereto, second and third drum sections hinged to the opposite ends of the first drum section, a key section intermediate the second and third sections, a bar supporting the key section and slidable on the chuck, links connecting the hinged section to the bar whereby movement of the key section inwardly of the drum will collapse the hinged sections after the key section, and means for collapsing and expanding the drum, said means being operatively associated with said bar. 85

9. A collapsible drum comprising a fixed section, a key section opposite the fixed section and movable toward and from the same, intermediate sections hinged on the fixed sec- 90

tion, and means actuated by movement of the key section for actuating the hinged sections, said means being operable to slightly expand the hinged sections as the key section is withdrawn from the drum circle.

- 5 10. A collapsible drum comprising a fixed section, a key section opposite the fixed section and movable toward and from the same, intermediate sections hinged on the fixed section, and means actuated by movement of the key section for actuating the hinged sections.
